DESIGN FOR A COMBINED ELECTRIC WASH- ING MACHINE AND WRINGER

William J. Russell, Mansfield, Ohio, assignor to
Westinghouse Electric & Manufacturing Com-
pany, a corporation of Pennsylvania

Application October 20, 1939, Serial No. 87,753

Term of patent 7 years

To all whom it may concern:

Be it known that I, William J. Russell, a citizen
of the United States, residing at Mansfield, in the
county of Richland and State of Ohio, have in-
vented a new, original, and ornamental Design for
a Combined Electric Washing Machine and
Wringer, of which the following is a specification,
reference being had to the accompanying draw-
ing, forming part thereof, in which:

Figure 1 is a perspective view, taken from the
front and one side of the combined electric wash-

ing machine and wringer, showing my new design;
Fig. 2 is a perspective view, taken from the rear
and other side of the article shown in Fig. 1;

Fig. 3 is a plan view of the article; and

Fig. 4 is a vertical diametric sectional view of
the top portion of the washing machine casing.

I claim:

The ornamental design for a combined electric
washing machine and wringer, substantially as
shown.

WILLIAM J. RUSSELL.
